INVENTOR.

William J. Dunsforth

BY

Thomas J. Dunsforth
ATTORNEY.

UNITED STATES PATENT OFFICE.

WILLIAM J. DUNSWORTH, OF DETROIT, MICHIGAN.

METALLIC AWNING.

Application filed June 11, 1926. Serial No. 115,278.

My invention relates to a new and useful improvement in a metallic awning, and has for its object the provision of a collapsible awning made from metal, which will be simple in structure, economical of manufacture, and highly efficient in use.

Another object of the invention is the provision of an awning adapted for mounting over window openings, door openings and the like, having a plurality of foldable metallic parts, each lower part or section being arranged to engage and move each upper succeeding part or section in unison with it.

Other objects will appear hereinafter.

15 The invention consists in the combination and arrangement of parts hereinafter described and claimed.

The invention will be best understood from a reference to the accompanying drawings 20 which form a part of this specification and in which,

Fig. 1 is a perspective view of the awning mounted over a window opening.

Fig. 2 is a sectional view taken on substantially line 2—2 of Fig. 1.

Fig. 3 is a sectional view taken on substantially line 3—3 of Fig. 2.

As shown clearly in Fig. 1 and Fig. 2 the awning comprises a plurality of sections, each 30 of which comprises a U-shaped member having a triangular shaped leg 7 and a triangular shaped leg 8, connected by a bight 9, which serves to form the cover of the awning, this portion 9 being, as shown in the drawings, 35 formed arcuate so that when the awning is lowered to operative position it will describe on its periphery an arc of a circle. The uppermost U-shaped member comprising the legs 8' and 7' which are connected by the 40 bight 9' is mounted upon the building, the lower end of the legs engaging a suitable bracket 11. Projecting outwardly from the rear edge of the leg 7' and 8' are flanges 7" 45 and 8" respectively. Projecting outwardly from the rear edge of the bight 9' is a flange 9". Suitable fastening or securing means may be projected through these flanges 7", 8" and 9" to secure the section to the wall of the building, so as to hang the awning formed 50 over the window opening 10. Pivots 100

nected at their lower ends to the lower ends of the leg 7" and 8" are the legs 7 and 8 of the various sections, suitable bolts or rivets 11 serving to bind these parts in pivotal relation. The forward edge of the bight 9" is 55 doubled upon itself on the undersurface to provide an abutment flange 12 which is adapted to engage the abutment flange 13 formed on the rear edge of the adjacent section, this flange 13 being formed by doubling over the 60 rear edge of the bight 9 over its upper surface. The forward edge of the bight 9" is doubled upon itself on its undersurface to provide an abutment flange 12" and the rear edge of the next lower section is doubled upon itself to 65 provide the abutment flange 13". It is evident, therefore, that as the sections are lowered each lower section will engage through its abutment flange 13 the abutment flange 12 on the forward edge of the next upwardly positioned section and draw it downward so that the sections are interlocked in this respect. By having these abutment flanges formed in this manner the legs 8 are 70 always overlapping at their edges so that the 75 various sections cannot pull apart.

Suitable pulleys may be arranged for raising the awning to inoperative position so that it may be folded comparatively flat against the side of the building when not in use. 80

While I have illustrated and described the preferred form of structure I do not wish to limit myself to the precise forms of structure shown but desire to avail myself of such variations and modifications as may come 85 within the scope of the appended claim.

Having thus described my invention what I claim as new and desire to secure by Letters Patent is:

A sectional awning of the class described 90 comprising a plurality of sections, each comprising a U-shaped member having a transversely arcuate bight and triangular shaped legs tapered toward their free ends; a U-shaped supporting member having triangular legs tapered toward their free ends; means for pivotally connecting the legs of said sections on the free ends of said supporting member's legs, said sections being adapted for folding into telescopic relation when in 95 100

inoperative position; a guide member projecting inwardly from the upper edge adjacent the outer end of each of said sections to provide a guide for a cord used therewith, and means for limiting movement of said sections relatively to each other and relatively to said supporting member when

10 moved to operative position and a flexible cord projected through said guides for moving said sections to inoperative position.

In testimony whereof I have signed the foregoing.

WILLIAM J. DUNSWORTH.
